UNITED STATES PATENT OFFICE.

WILLIAM RAINVILLE, OF WOONSOCKET, RHODE ISLAND.

SADDLE FOR THE TOP ROLLS OF SPINNING-MACHINES.

No. 822,075.

Specification of Letters Patent.

Patented May 29, 1906.

Application filed November 18, 1905. Serial No. 287,959.

To all whom it may concern:

Be it known that I, WILLIAM RAINVILLE, a subject of the King of Great Britain, residing at Woonsocket, in the county of Providence and State of Rhode Island, have invented new and useful Improvements in Saddles for the Top Rolls of Spinning-Machines, of which the following is a specification.

My invention pertains to saddles for the top rolls of spinning-machines; and it contemplates the provision of a saddle which in addition to being simple and inexpensive and well adapted to withstand the usage to which such devices are ordinarily subjected is constructed in such manner that all that is necessary in order to place pressure on or remove pressure from the middle roll is to reverse the saddle.

Other advantageous features peculiar to my invention will be fully understood from the following description and claims when the same are considered in connection with the accompanying drawings, forming part of this specification, in which—

Figure 1 is a side elevation of so much of a spinning-machine as is necessary to illustrate my invention with my novel saddle in position to press on the middle roll. Fig. 2 is a similar view with the saddle reversed to remove pressure from the middle roll, and Fig. 3 is a front elevation with the saddle arranged in the same manner as in Fig. 1.

Similar letters designate corresponding parts in all of the views of the drawings, referring to which—

A is the front roll, B the middle roll, and C the rear roll, of a spinning-machine.

D is the body of the saddle constituting the present and preferred embodiment of my invention.

E is the spring of the saddle, and F is the rod for connecting the saddle-body with the ordinary weighted lever, which latter I have deemed it unnecessary to illustrate.

The saddle-body D is formed of one piece of any material compatible with the purpose of my invention and comprises a longitudinal portion a, adapted to bear on the rear wall C and having ducts b at intermediate points in its length for supplying the rear and middle rolls with lubricant and also having

seats c in the lower and upper edges of its forward portion for the adjustable connection of the rod F and a head d extending in opposite directions from the forward end of the longitudinal portion and having concave bearings e at its ends and also having a lubricant-duct f extending throughout its length and between said bearings e.

The spring E is fixed at one of its ends to one edge of the longitudinal portion a of the body D at an intermediate point in the length of said portion and is arranged, as shown, so as to exert pressure on the middle roll B when the saddle is in the position shown in Fig. 1 and leave said middle roll free from pressure when the saddle is reversed, or in the position shown in Fig. 2.

As is well known in the art, it is necessary in some cases to impose weight or pressure on the middle roll of a spinning-machine and in others to relieve the middle roll of weight or pressure. Now when my novel saddle is employed and it is desired to relieve the middle roll of weight or pressure the same can be accomplished by simply reversing the saddle—i. e., turning the same on its axis from the position shown in Fig. 1 to the position shown in Fig. 2—since when this is done the spring E is placed uppermost and away from the middle roll. When, on the other hand, it is desired to subject the middle roll to weight or pressure, the saddle can be readily restored to the position shown in Fig. 1, with the spring E bearing on the said middle roll.

I claim—

1. A saddle for top rolls comprising a body having a longitudinal portion and a head extending in opposite directions from the longitudinal portion and provided at its ends with bearing portions, and a spring carried by the longitudinal portion of the body and adapted in one position of the body to exert pressure or weight on the middle one of the top rolls.

2. A saddle for top rolls comprising a body having a longitudinal portion provided with lubricant-ducts and seats at the lower and upper edges of its forward portion and also having a head extending in opposite directions from the forward end of the longitudinal portion and provided at its ends with

concave bearings and also provided with a duct extending between said bearings, and a spring carried by the longitudinal portion of the body and adapted in one position of the body to exert pressure or weight on the middle one of the top rolls.

5 In testimony whereof I have hereunto set

my hand in presence of two subscribing witnesses.

WILLIAM RAINVILLE.
